UNITED STATES PATENT OFFICE.

JOSEPH H. NOTT, OF CHICAGO, ILLINOIS, ASSIGNOR TO REX GOLF MACHINE COMPANY, OF CHICAGO, ILLINOIS, A CORPORATION OF ILLINOIS.

GOLF DRIVING-MACHINE.

1,216,970.

Specification of Letters Patent.

Patented Jan. 2, 1917.

Application filed August 2, 1915. Serial No. 43,123.

To all whom it may concern:

Be it known that I, JOSEPH H. NOTT, a citizen of the United States, and a resident of the city of Chicago, in the county of Cook 5 and State of Illinois, have invented certain new and useful Improvements in Golf Driving-Machines; and I do hereby declare that the following is a full, clear, and exact description of the same, reference being had 10 to the accompanying drawings, and to the numerals of reference marked thereon, which form a part of this specification.

It has been found difficult, if not impossible, for persons interested in golf to practice with the long shot clubs, such as driver, brassie, or iron, except on a links or driving court, and even if such is available it is sometimes difficult to measure or ascertain 15 the distance covered by the ball. Then, too, the player is not enabled to make an accurate comparison between the results gained by the use of different clubs, and furthermore the number of golf balls and time required in many instances makes this form of 20 practice undesirable.

This invention relates to a means for accurately determining the impact imparted to a golf ball to measure the distance which would ordinarily be covered by the ball under normal conditions if allowed to travel 25 unhindered through the air.

It is an object of this invention to construct a device consisting of a golf ball connected by means of a restraining cord to a 30 measuring device for indicating substantially the distance which would be covered by the ball when struck by a club were the ball allowed free flight.

It is also an object of this invention to 35 construct a device embracing a measuring means with a restraining cord attached thereto having connected at its end a golf ball which when struck by a golf club, serves to move said measuring means against a resilient and frictional resistance to a fixed position indicating substantially the impact 45 imparted to the ball.

It is also an object of this invention to 50 construct a device embracing a pivotally mounted member adapted to move against an increasing resistance and to receive its movement from a connected cord attached to

a golf ball adapted to be struck by a golf club in the hands of a player.

It is furthermore an important object of 55 this invention to construct a device embracing means movable over a graduated scale against an increasing resistance and attached by means of a line to a golf ball, whereby the extent of the flight which would 60 otherwise be taken by the ball were it free, is measured by the means which restrains the ball and brings the same to rest.

It is finally an object of this invention to 65 construct a device simple in construction and operation for effectually measuring the impact to a golf ball imparted by a golf club.

The invention (in a preferred form) is 70 illustrated in the drawings and hereinafter more fully described.

In the drawings, Figure 1 is a top plan view of a device embodying the principles of my invention. Fig. 2 is a side elevation thereof showing the same in position for use. Fig. 3 is a detail sectional view with 75 parts shown in elevation taken on line 3-3 of Fig. 1, and showing the operation in dotted lines. Fig. 4 is a section taken on line 4-4 of Fig. 3. Fig. 5 is a fragmentary top plan view of the cable or line connection 80 to the movable measuring arm. Fig. 6 is a detail view of the sling for securely holding the ball. Fig. 7 is a fragmentary view partly in section, showing a modified construction differentiated from that shown in 85 Fig. 4. Fig. 8 is an inner face view of a golf ball attached in the sling. Fig. 9 is a side view thereof.

As shown in the drawings, the frame of 90 the machine consists of a base, the extremities of which spread outwardly, as denoted by the reference numerals 1, 2, 3, and 4, all of which, however, are part of an integral casting and serve to support attached thereto on the two halves 5 and 6, of a quadrant 95 shaped frame member. Said respective frame sections 5 and 6, are held rigidly connected one to another by means of bolts or rivets 7, connected thereto at various points, and said frame members are each cut away 100 along their upper edge to afford a slot therebetween. The purpose of said slot is to permit a swinging movement to an arm or lever 8, said arm being mounted upon a

- pivot pin or bolt 9, extending between said respective frame members at the lower central portion thereof. Mounted between said respective frame members 5 and 6, and inclosed thereby is a curved resilient bar 10, the ends of which are fitted into recessed lugs 11, formed on the interior of one of said frame members and which is braced intermediate its ends by clips 12. The arc of curvature of said resilient bar is eccentric with respect to the pivot pin 9, of the lever 8, so that as the lever swings from the position shown in full lines in Fig. 3, to the dotted line position, a curved extension 13, which is formed on said lever, wedgingly engages said resilient bar after the lever moves to and beyond upright position, so that a continually increasing resistance is thus offered to the movement of said lever.
- The outer end of said arm 8, is extended in opposite directions to afford substantially a T, and one end of said extended portion is yoked as indicated by the reference numeral 14, to receive pivoted thereto a lever 15. As clearly shown in Figs. 1 and 2, a series of gradations 16, is formed on the upper portion of the respective frame members 5 and 6, to indicate the distance which would have been taken by the ball in flight were it not restrained in the manner hereinafter described. For this purpose a sling of leather or other suitable material, denoted by the reference numeral 17, is provided, and is adapted to engage around a ball 18, leaving one side of the same exposed and to be retained thereon by a line or cord 19, engaged through apertures provided in the sling, with the other end of the cord, which may be from ten to twenty feet in length, attached to a coiled spring 20, which is in turn connected to the lever 15. The cord 19, is so connected through the ends of the sling 17, that tension on said cord serves to further tighten the sling around the ball.
- When the device is used, a mat 21, may be placed along side of the frame in the manner shown in Fig. 1, and the ball laid thereon, to be struck by a golf club. The line or cord 19, is then laid evenly in front of the machine to run out easily without tangling when the ball is driven away from the machine.
- In the modification illustrated in Fig. 7, I have shown a pin 22, secured in the lever 8, to bear upon the upper curved portion of the spring 10, to replace the integral curved portion 13, already described.
- The operation is as follows: The ball is laid upon the mat 21, in a convenient position to be struck by a golf club, and when so struck flies outwardly until the limit of the cord or line 19, is reached, whereupon the pivoted arm or lever 8, is caused to swing in the frame, bearing with a certain resistance upon the resilient bar 10, and when the ball
- comes to rest, said arm or lever 8, is frictionally held in its extreme position of movement. The gradations 16, denote what would have been the distance flight of the ball, and of course the ball may then be drawn back by means of the cord 9, and the practice stroke repeated. This enables a player to make comparisons of shots with clubs of different length and weight to ascertain which are most suitable for use. The lever 15, connected on the upper end of the arm 8, serves to impart the proper pull transmitted from the cord or line 19, and the small coiled spring 20, prevents sudden jerking stress being applied to the cord 19, which might possibly cause breaking of the same.
- The frame of the device is preferably made comparatively heavy, so as not to be affected by sudden stoppage of the ball in flight. The device is capable of many uses, not only in golf instruction and practice, but may also be used for indoor golf games.
- I am aware that various details of construction may be varied through a wide range without departing from the principles of this invention, and I therefore do not purpose limiting the patent granted otherwise than necessitated by the prior art.
- I claim as my invention:
1. In a device of the class described, a sling adapted to be attached to a golf ball leaving one side of the latter exposed, a line connected with said sling, and measuring mechanism connected to said line to check the flight of the golf ball, when struck, to measure the energy of flight thereof. 95
  2. In a device of the class described, a sling adapted to be attached to a golf ball leaving one side of the latter exposed, a line connected with said sling and forming the means for retaining the latter in its engagement with the golf ball, and measuring mechanism connected to said line to check the flight of the golf ball, when struck, to measure the energy of flight thereof. 105
  3. In a device of the class described, a line adapted to be attached to a golf ball, a movable arm to which said line is connected, and means offering a progressively increasing resistance to the movement of said arm and acting to hold said arm in any adjusted position to indicate the energy of flight of the golf ball. 115
  4. In a device of the class described, a line adapted to be attached to a golf ball, a resilient element attached to said line, a movable arm to which said resilient element is connected, and means offering a progressively increasing resistance to the movement of said arm and acting to hold said arm in any adjusted position to indicate the energy of flight of the golf ball. 120
  5. In a device of the class described, a line adapted to be attached to a golf ball, a 130

pivoted arm to which said line is connected, a curved resilient bar disposed eccentric to the pivot of said arm, and means engaging said arm and bar, whereby said bar affords 5 a progressively increasing resistance to the movement of said arm to check the flight of the golf ball, when struck, and to measure the energy of flight thereof.

In testimony whereof I have hereunto subscribed my name in the presence of two sub- 10 scribing witnesses.
